UNITED STATES PATENT OFFICE

2,472,338

WEDGE LOCKED, SLIDING SIDE JAW
WRENCH

Eric Ludvig Leonard Österdahl, Stockholm,
Sweden, assignor to E. A. Bergs Fabriks Aktie-
bolag, Eskilstuna, Sweden, a joint-stock com-
pany of Sweden

Application March 9, 1945, Serial No. 581,736
In Sweden February 1, 1944

1 Claim. (Cl. 81—151)

1

The present invention relates to a rapidly adjustable wrench which steadily maintains its adjustment during operation, which does not loose its grip by wear, and which, moreover, is simple and cheap to manufacture. The invention relates to a wrench mainly consisting of a handle with a fixed jaw, a movable jaw and a locking member. The characteristic feature of the invention is that the movable jaw slides on the outside of the handle and that the locking member consists of two parts of the same shape, one on each side of the handle, which parts are connected with each other, and that the two planes coinciding with those surfaces of the handle and of the movable jaw which co-operate with the locking member, form an angle with each other and with the direction of motion of the movable jaw in such a way that, when the wrench is used, the working force of the jaws tends to displace the locking member in the direction towards the surfaces of the handle cooperating with the said locking member.

The invention is illustrated on the accompanying drawing. Fig. 1 shows a side view and Fig. 2 shows an end view of the head of the wrench with removed locking member. Figs. 3 and 4 show side views of the head of the wrench with two embodiments of the locking member.

1 indicates the handle, which is provided with a fixed jaw 11 and a movable jaw 2, the latter being shaped to two legs 12, 13, embracing the handle and located one on each side of the handle. The locking member 8 consists of two equal parts or halves which are also located one on each side of the handle 1 and which are held together by a transversal rivet, bolt or the like 9. The handle 1 and the movable jaw 2 have surfaces 3, 4, which cooperate with the locking member 8. These surfaces 3, 4 form an angle with each other and with the direction of motion of the movable jaw 2 (see the arrows 10 in Fig. 1) in such a way that the working force of the movable jaw tends to separate this jaw from the handle 1. Some of the surfaces which cooperate at the locking may be treated in such a way as to increase the friction, but this is not absolutely necessary. The handle 1 is provided with a recess 5 (Fig. 1) for the rivet or bolt 9 holding together the two parts or halves of the locking member 8. In this recess 5 a spring 6 is preferably placed having for its object to keep the locking member 8 constantly engaged with the surfaces

2

3, 4 of the handle 1 and of the movable jaw 2. According to Fig. 3 each part or half of the locking member 8 consists of a roll, a small wheel or the like. In Fig. 4, on the contrary, 5 each part or half of the locking member 8' consists of a wedge-shaped member, in which case the pressure produced upon the locking member is distributed over larger surfaces, whereby the quality of the material of the locking member is of less importance. Other embodiments are, of course, also imaginable within the scope of the invention.

10 Among other advantages of the invention which have not been indicated above it may be mentioned that the movable jaw 2 gets a solid support from the locking member 8 also in the lateral direction.

15 Having now described my invention, what I claim as new and desire to secure by Letters 20 Patent is:

A wrench including a handle provided with a transverse opening and having correspondingly inclined shoulders on opposite sides thereof directly beneath and parallel with the bottom 25 of the opening, a fixed jaw on the outer end of the handle, a bifurcated movable jaw straddled about the outer end of the handle for lateral sliding movement thereon relative to the fixed jaw, said movable jaw including identical leg 30 portions having correspondingly inclined inner edges positioned at an angle relative to the shoulders and to the direction of movement of the movable jaw, a locking member including two identical parts positioned on opposite sides 35 of the handle, a pintle extending through the opening for free movement therein and operably connecting the parts of the locking member together, and a spring seated in the opening and carrying the pintle for yieldably holding said locking parts against the inclined edges of the movable jaw and the shoulders on the handle.

ERIC LUDVIG LEONARD ÖSTERDAHL.
